REFUSE INCINERATOR

Filed Sept. 17, 1921

Inventor:

Jesse Prescott

by

Henry Brown Dryden, May

S. Phillips.

UNITED STATES PATENT OFFICE.

JESSE PRESCOTT, OF WEBSTER, MASSACHUSETTS.

REFUSE INCINERATOR.

Application filed September 17, 1921. Serial No. 501,844.

To all whom it may concern:

Be it known that I, JESSE PRESCOTT, a citizen of the United States, residing at Webster, in the county of Worcester and 5 State of Massachusetts, have invented new and useful Improvements in Refuse Incinerators, of which the following is a specification.

This invention relates to incinerators or 10 crematories for burning garbage and refuse of all kinds.

The object of the invention is to provide an incinerator for use in apartment buildings, flats, hospitals, public institutions and 15 residences, so constructed and arranged that the refuse may be consumed after it has been delivered to the burner from various floors of the building in which the same is installed.

20 In carrying out my invention, I utilize a furnace having a combustion chamber to which fuel may be delivered for the consumption of the refuse, a smoke pipe for carrying away the products of combustion, 25 and a chute adapted to deliver the refuse into the combustion chamber and extending upwardly past the several floor levels of the building with normally closed hoppers leading from each floor level to the chute. The 30 smoke flue and the refuse chute may be located in the usual built-in chimney with which such buildings are provided, so that the chute constitutes as it were a flue of the chimney which is cut off from and independent of the smoke flue or flues of the 35 same chimney. The lower end of the chute, at its junction with the combustion chamber, is preferably provided with a normally closed valve, which, however, is so lightly 40 balanced that it will be opened by the weight of the refuse falling thereon through the chute. This valve prevents the products of combustion from entering the refuse chute but opens automatically to permit the 45 delivery of the refuse into the combustion chamber.

On the accompanying drawings,—

Figure 1 represents in section an incinerator embodying my invention and shows 50 the same as installed in a building.

Figure 2 represents a front elevation of a portion of the same.

Figure 3 represents an enlarged vertical section through the delivery chute and

shows the construction of the hoppers which are located at different floor levels.

Figure 4 represents an enlarged vertical section through the furnace or incinerator.

Figure 5 represents a horizontal section on the line 5—5 of Figure 1.

Figure 6 represents a section on the line 6—6 of Figure 4.

As illustrated on the drawings,—the incinerator proper may be built in the lower end of a chimney, which is indicated as a whole

at 10. This incinerator comprises a combustion chamber 11, the rear and side walls of which may be formed of fire brick or other suitable material as indicated at 12.

The front of the incinerator consists of a large plate or casting 13 having a front wall 14 which may be flush with the face of the lower portion of the chimney, as shown in

Figures 1, 2 and 4, and with an inner plate 15 which forms the front wall of the combustion chamber 11. These two walls provide a relatively large insulating air space

16 at the front portion of the incinerator. Any suitable means may be utilized for receiving and supporting the refuse during its consumption and for supplying fuel for insuring the combustion of such refuse. As indicated, however, I have illustrated the

wall 15 as being provided with a plate 17 supported by brackets 18 on which may be supported a basket or holder for the refuse.

This plate 17 is shown as being substantially rectangular so as to form a horizontal partition, and it is provided with a dropping

grate section 19 controlled by a handle bar 20. The basket or holder 21 for the refuse is frusto-pyramidal and rests on and is secured to the support 17. Across the corners

of the combustion chamber there are plates 22 which extend from the support 17 upwardly to a point below the top of the combustion chamber to afford flues having openings extending into the combustion chamber

substantially as illustrated and described in my Letters Patent No. 1,093,856, dated

April 14, 1914, to which reference may be had for a more detailed description.

Below the basket an ash pan 23 is supported on the base of the ash pit indicated

at 24, and said ash pan may be withdrawn through an opening 25 in the front wall of

the incinerator, which opening is normally closed by a hinged door 26. The floor of

the ash pit may be made of a hydraulic cement, fire brick or other suitable material.

At 27 I have indicated a fuel supply pipe for the supply of fuel to the burner which is indicated as a whole at 28. Between the burner and the supply pipe there is a conduit 29 and a mixer 30, substantially as described in the Letters Patent herein referred to. Access may be had to the basket or holder 21 for the burning refuse through openings 31, 32, formed in the front plates 14 and 15 and normally closed by the hinged doors 33, 34.

Provision is made for delivering refuse directly into the combustion chamber through a hopper 35 having a door 36 hinged thereto at 37. This door is provided with the usual dumping member 38 which closes the opening into the hopper when the door is opened to its greatest extent, it and the door member 36 forming a receptacle to receive the garbage or other refuse when the door is opened. On the closure of the door, the contents of the receptacle thus formed are dumped into the incinerator basket 21. This dumping door is provided for the use of the janitor or those on the floor level where the incinerator proper is located.

The upper portion of the combustion chamber of the incinerator is illustrated as closed by a top plate or member 39, having an opening 40 in its forward portion which communicates with a smoke flue 41 extending upwardly through the chimney and terminating at the upper end thereof so as to deliver the products of combustion to the atmosphere. Assuming that the chimney is built of brick, I have illustrated this smoke flue as being provided with the usual flue lining 42. In the rear of the smoke flue I have provided an elbow 43, the lower end of which is adapted to communicate with the combustion chamber and to deliver refuse passing therethrough into the basket 21. This elbow may be formed integrally with the plate 39 or separately therefrom as most convenient, its upper end terminating in a flange 44 into which may project the lower end of the lining 45 of a garbage chute which is formed in the chimney. This passageway or chute is indicated at 46 and extends vertically and upwardly through the chimney and terminates at the end thereof, being open thereto to the atmosphere. With convenience the flue lining 45 may consist of sections of cylindrical tile or earthenware pipe. Hinged at 47 to a lug 48 at the delivery end of the elbow 43, there is a door or valve 49 whose function is to close the lower end of the elbow and thus close the lower end of the delivery chute for the refuse. A weighted arm 50 is connected to the door or valve 49 and is sufficiently large to hold the valve

closed, and yet to permit it to open when any garbage or refuse material impinges or rests thereon so as to permit it to be delivered into the refuse basket 21 of the incinerator.

While, of course, the chimney may be located at the outer wall of a building, nevertheless in many cases it extends upwardly through the building with rooms or passageways on both sides thereof, and in Figure 1 I have illustrated a portion of the building as having floors *a b c* with rooms or passageways on both sides of the chimney 10, so that access may be had to the chute from both sides of the chimney.

At a convenient point above each floor level, normally closed openings are provided through which garbage and other refuse may be delivered into the chute 46. During the construction of the chimney there may be placed between sections of the chute lining 45 a joint or fitting 51 having upwardly inclined branches 52 into which may telescope the hoppers 53, as shown in Figure 3, the hoppers terminating at the front and rear walls of the chimney and extending if desired through the wall finish which is indicated at 54. A dumping door 55 is pivoted at 56 to each of the hoppers, the door proper 57 being provided with a handle 58. With convenience each hopper or laterally inclined portion of the chute may be provided with an ornamental flange 59 to rest against the wall finish.

In an incinerator such as described, in which the chute for the refuse is separate from the smoke flue but is, like such flue, located in the chimney, I secure an economy of space, and at the same time, by providing an automatic valve closing the lower end of the chute, I prevent any possibility of products of combustion or odors from passing upwardly through the chute and out into the rooms or passageways of the building in which the incinerator is located. A further advantage of this construction is that, when the doors leading into the chute are open for the deposit of garbage or other refuse material into the chute, there is practically no opportunity for the products of combustion to pass outwardly therethrough. Again, it will be observed that the furnace or combustion chamber is located almost directly below the chute, which extends directly therefrom upwardly in a vertical direction to the top of the chimney, so that there is a clear passageway, unobstructed save for the door 49, through which the refuse material may be dumped directly into the combustion chamber. The whole construction is simple; access may be easily had to the garbage basket or holder 21; and by removing the dumping door 36, one may have access to the hinged valve 49 at the lower end of the chute.

What I claim is:—

1. A garbage and refuse incinerator for a building having a built-in chimney, comprising a combustion chamber having there-
5 in a receptacle for the material to be con-
sumed and a burner for a suitable fuel, and
said chimney having a smoke flue therein
leading directly from the combustion cham-
ber for the products of combustion, and also
10 having a separate refuse chute or flue there-
in open at its upper end to the atmosphere
and at its lower end leading into the said
combustion chamber.

2. A garbage and refuse incinerator com-
15 prising a chimney having two flues therein,
one for carrying away products of combus-
tion, and the other opening into the atmos-
phere and having lateral door-closed hop-
pers and serving as a chute for delivering
20 refuse material into the combustion cham-
ber, and a combustion chamber located di-
rectly below said flues and communicating
therewith.

3. A garbage and refuse incinerator com-
25 prising a built-in chimney having two flues
therein, both having their upper ends open-
ing into the atmosphere, one for carrying
away products of combustion, and the other

having lateral door-closed hoppers and serv-
ing as a chute for delivering refuse material 30
into the combustion chamber, a combustion
chamber located directly below said flues
and communicating therewith, and an auto-
matic valve normally closing the lower end
35 of the refuse chute.

4. A garbage and refuse incinerator com-
prising a brick or masonry chimney having
therein separate vertical flues opening into
the atmosphere at their upper ends, one for
carrying away products of combustion and 40
the other having lateral door-closed hoppers
and serving as a chute for refuse material,
a combustion chamber located in the base
of the chimney and having the lower ends
45 of the said flues opening directly into the
upper end thereof, a basket or receptacle for
the refuse material and a burner both located
in said chamber, with the receptacle in posi-
tion to receive refuse material delivered
50 from the chute, and a weighted normally-
closed valve at the lower end of said chute
for preventing the passage of the products
of combustion through said chute.

In testimony whereof I have affixed my
signature.

JESSE PRESCOTT.
